UNITED STATES PATENT OFFICE.

BASCUM O. AUSTIN AND WILLIAM G. HORN, OF WILKINSBURG, PENNSYLVANIA, ASSIGNEES TO WESTINGHOUSE ELECTRIC AND MANUFACTURING COMPANY, A CORPORATION OF PENNSYLVANIA.

FUSE MECHANISM.

Application filed March 5, 1921. Serial No. 449,793.

To all whom it may concern:

Be it known that we, BASCUM O. AUSTIN, a citizen of the United States, and a resident of Wilkinsburg, in the county of Allegheny and State of Pennsylvania, and WILLIAM G. HORN, a subject of the King of Great Britain, and a resident of Wilkinsburg, in the county of Allegheny and State of Pennsylvania, have invented a new and useful Improvement in Fuse Mechanism, of which the following is a specification.

Our invention relates to fuse mechanism and particularly to fuse mechanism for high-potential circuits such as are employed on electric locomotives and the like.

One object of our invention is to provide a fuse box wherein the fuse is mounted in an enclosing holder that may be turned to a position wherein the fuse terminals are disengaged from the live terminals of the circuit and, consequently, are safe to handle. By reason of this arrangement, the practice of disengaging the contact shoe of the locomotive from the feed conductor is obviated and, as a consequence thereof, considerable time is saved in renewing the fuse.

Another object of our invention is to provide a fuse mechanism wherein the fuse connections to the contact terminals are positively secured and wherein the connecting means is operable from the exterior of the box housing and serves to positively hold the fuse holder and the terminal housing in closed operative position.

Another object of our invention is to provide a fuse mechanism wherein the fuse holder is pivotally attached to the terminal housing whereby two different motions of the holder with respect to the housing are necessary before access may be had to the fuse within the holder. By reason of this method of mounting, interlocking means between the terminal housing and the fuse holder must first be released by a disengaging movement which tends to disconnect the fuse from the contact terminals in the housing before rotary opening movement of the holder is permitted.

Another object of our invention is to provide a simple housing wherein the housing members may readily be molded of insulating compound.

A fuse mechanism wherein the fusible element is securely clamped to contact mem-

bers within the holder by means of wedges 55 operated by insulated hand screws and wherein the contact members are provided with projecting wedges that are positively held in engagement with the contact terminals by means of insulated hand screws. 60

These and other objects, that will be made apparent throughout the further description of the invention, are attained by means of the fuse mechanism hereinafter described, and illustrated in the accompanying drawings, wherein:

Figure 1 is a view, partly in section and partly in side elevation, illustrating our improved switch mechanism;

Fig. 2 is an end elevational view of the apparatus shown in Fig. 1; and

Fig. 3 is a section on the line III—III of Fig. 1, showing a portion of the mechanism.

Referring to the drawings, the apparatus 75 includes a metallic support member 4 to which an overhung contact terminal housing 5, made of molded insulating compound, is secured by means of bolts 6. A metal hinge member 7 is secured to the support 4 by 80 screws 8. This member is provided with two downwardly extending forked projections 9 having vertical slots 11 disposed therein for receiving a hinge pin 12, the purpose of which will herein- 85 after appear.

The housing 5 is provided with a pair of separate contact-terminal members 13 that are made of conductive material and are provided with terminal clamps 14 by 90 which the contact terminal is clamped to a feed conductor 15 by means of bolts 16. The contact terminals 13 are disposed in opposite ends of the housing, only one of them being illustrated in Fig. 1. It will be understood that the apparatus, shown in side elevation in Fig. 1, is an exact duplicate of the mechanism illustrated in the left half portion of the figure.

The contact terminals 13 are secured to the housing 5 by means of screws 17. The lower edge of the contact terminal 13 is provided with a slot 18 having tapered contact walls 19 that are adapted to receive a wedge-shaped extension 21 that is an integral part of a contact member 22 to be hereinafter described.

The contact terminal 13 is also provided

with a perforation 23 through which a threaded screw member 24 is inserted. Longitudinal displacement of the screw member 24, with respect to the contact 13, is prevented by a screw 25 which projects into an annular groove 26 that is provided in the shank of the screw 24. The outer end of the screw 24 is provided with an enlarged head 27 about which a hand wheel 28 of insulating compound is molded.

The upper portion of the housing 5, adjacent to the pin 24, is provided with a perforation 29 into which a cylindrical neck 31 of the contact terminal 13 projects. This neck serves to center the contact member during the assembling operation. An integral annular ridge 32 projects upwardly from the housing 5 and surrounds the opening 29 to prevent water or foreign materials from gaining access to the interior of the housing. The underside of the hand wheel 28 is provided with an annular groove 33 into which the upper edge of the annular ridge 32 projects. It is, therefore, impossible for rain water to gain access to the interior of the housing.

A fuse holder 36 includes a metal bracket 37 that is hinged to the extensions 9 by means of the hinge pins 12, and an insulating fuse housing or holder 38 is secured to the bracket 37 by means of the bolts 39. The housing 38 is made of molded insulating compound and is provided with an operating handle 41 by means of which the housing 38 may be turned to open position, as indicated in the dotted lines in Fig. 2.

The housing consists of an open inner side 42 that lies contiguous to the insulating wall 43 of the housing 5 when the holder is in closed position. The top portion of the holder 38 is also open and is adapted to be closed by the overhung housing 5 when the holder 38 is moved into a position wherein the fuse-contact terminals 22 are in operative engagement with the contact terminals 13.

The contact terminals 22 are disposed in opposite ends of the holder 38 and are attached thereto by means of screws 44. Each fuse-contact member 22 is provided with a groove 45 having the lowermost wall 46 thereof inclined with respect to the upper wall 47. A metal wedge block 48 is inserted within the groove 45 for the purpose of clamping the fusible element 49 between the wedge block and the lower portion of the fuse-contact member 22.

The fuse-contact terminal is provided with a perforation 51 through which a screw member 52 is inserted. The screw member is held against relative longitudinal movement with respect to the contact member 22 by means of a screw 53 that projects into an annular groove 54 provided in the screw 52. The outer end of the screw is provided

with an enlarged head 55 about which is molded a hand wheel 56 that consists of insulating compound.

Each end of the housing 38 is provided with an opening 57 through which the screw 52 and the inner collar of the hand wheel 56 extend. The openings 57 are surrounded by means of integral annular collars 58 for the purpose of preventing moisture and foreign objects from entering the holder. The hand wheels 56 are grooved in a manner similar to the hand wheels 28 and for the same purpose.

The threaded end of the screw 52 is normally in threaded engagement with the wedge block 48 and, consequently, when the handle 56 is rotated, the screw 52 is similarly rotated, and the wedge block 48 moved into and out of clamping position.

The fuse 49 is positioned adjacent its center by means of an insulating bridge or projection 59 that is an integral part of the housing. The lower central portion of the housing is provided with a downwardly extending conduit 61 which provides an outlet 90 for the gases generated by the explosion or rupture of the fuse.

The underside of the overhung housing 5 is provided with a channel 62 in which a pliable insulating packing 63 is secured. The upper edge of the holder 38 is formed in the shape of a ridge 64 that is similar in contour to the groove 62 and projects into the groove into engagement with the packing to form a substantially moisture-proof and dust-proof joint between the upper face of the holder and the end face of the overhung housing.

As previously stated, when the fuse-contact member 22 is in operative conductive engagement with the contact terminals 13, the tapered projections 21 of the former project into the tapered grooves 18 of the latter. The holder and the housing are retained in the closed operative position, indicated in Fig. 1, by means of the screws 24 that are operated by the hand wheels 28. It will be apparent from the foregoing that, in order to open the fuse holder, the holder must first be lowered until the ends of the projections 21 clear the lower face of the overhung housing. This lowering movement is accomplished by so turning the hand wheels 28 simultaneously that the housing is lowered by the action of the screws 24 which have threaded engagement with the projections 21. The slots 11 in the projections 9 of the support permit of this lowering movement.

When the holder has been lowered to a position wherein the projections 21 clear the lower face of the housing 5, the screws 24 are disengaged from the projections 21. The holder may then be swung to the open position, indicated in broken lines in Fig. 2,

wherein the fuse contact members are disengaged from the live contact terminals 13.

In order to renew the fuse, the hand wheels 56 are turned to move the wedge blocks 48 toward the center of the box. The remains of the exploded fuse may then be removed from the contact members 22 and a new fuse 49 inserted. The hand wheels 56 are then turned to draw the wedge blocks 10 48 into clamping engagement with the new fuse. After the fuse has been replaced, the holder 38 is turned upward until the entire side face thereof engages the side of the support. The fuse-contact members 22 are 15 then registered with the contact terminals 13, and the housing is then moved upwardly by the operator until the projections 21 are brought into contact with the lower extremities of the screws 24. The holder is 20 held in this position until the threads of the screws 24 are brought into operative engagement with the projections 21. The hand wheels 28 are simultaneously rotated until the contact members 22 are brought 25 into operative conductive engagement with the contact terminals 13.

It will be apparent from the foregoing that the screws 24 serve to positively connect the fuse-contact members 22 and the 30 contact terminals 13 and to positively hold the holder in closed operative engagement with the housing 5. The construction is compact, is substantially water-proof and is safe to operate.

35 While we have described and illustrated but one embodiment of our invention, it will be apparent to those skilled in the art, that various modifications, substitutions, changes, omissions and additions may be made in the 40 apparatus described and illustrated without departing from the spirit and scope of the invention, as set forth in the appended claims.

We claim as our invention:—

45 1. Fuse mechanism comprising a support, a contact terminal secured to the said support and having a socket therein, a fusible element, a holder for the fusible element pivoted to the said support and having a 50 tapered extension fitting into the said socket and preventing rotary movement of the holder when the latter is in operative position and means extending through the socket and engaging the said extension for displacing the holder to permit of rotary movement thereof.

55 2. Fuse mechanism comprising a support, a contact terminal secured thereto, a fusible element, a holder therefor pivoted to the support and movable into engagement therewith and a locking means for sliding the holder radially with respect to the axis of rotation thereof and for releasing the holder and the support for permitting relative rotary movement of the holder when

the said means has moved a predetermined distance.

3. Fuse mechanism comprising a pair of supporting members having a slot-and-pin connection, a contact terminal secured to one of the members, a fusible element secured to the other member and means for relatively moving the members radially with respect to the axis of the pin whereby the contact terminal and the fusible element are 75 moved into operative engagement.

4. Fuse mechanism comprising a pair of hinged supporting members having a slot-and-pin connection, a contact terminal secured to one of the members, a fusible element secured to the other member and being accessible when the members are in angular relation with one another and interlocking means on the members movable into interlocked relation by relative movement of the 85 members other than angular movement.

5. Mechanism comprising a pair of members attached to one another for relative angular and sliding movements, a contact terminal in one member, a conductor element in 90 the other member that is accessible when the members are in angular relation and interlocking terminals on the members for preventing relative angular movement of the members when the members have been 95 slidably moved a predetermined distance with respect to one another and externally operative means carried by the terminals for locking the members and terminals in operative position.

6. Mechanism comprising a pair of interlocked housing members hinged together by a slot-and-pin connection and separable a limited distance by relative movement first in a substantially radial direction with respect to the hinge and then by rotary angular movement, and separate contact members within the housing, the said contact members being connected when the housing members are in interlocked relation.

100 7. An electrical fixture comprising a pair of joined and interlocked housing members hinged together by a slot-and-pin connection and being separable by relative movement first in the plane of joinder thereof and then by rotary angular movement.

105 8. An electrical fixture comprising a pair of joined and interlocked housing members hinged together by a slot-and-pin connection and separable by relative movement first in the plane of joinder thereof and then by rotary angular movement and means for relatively moving the members in the plane of joinder thereof.

110 9. Mechanism comprising a pair of joined housing members hinged together by a slot-and-pin connection for relative rotary and sliding movement and contact members carried by the housing members and adapted to be connected when the housing members are 115 120 125 130

relatively moved in the plane of joinder thereof.

10. Mechanism comprising a pair of joined housing members hinged together by a slot-and-pin connection for relative rotary and sliding movement, contact members carried by the housing members and adapted to be connected when the housing members are relatively moved in the plane of joinder thereof, the said contact members having interlocking means whereby rotary movement of the housing is prevented so long as the contact members are connected.

11. Fuse mechanism comprising a support having an overhung housing for enclosing a contact terminal, a fuse holder pivoted to the support and having a fuse, a contact member registering with the contact terminal when the fuse holder is in its closed position with respect to the housing, and means whereby the holder is bodily moved toward the overhung housing to connect the contact terminal with the contact member and to close the space between the housing and the holder.

12. Fuse mechanism comprising a support having an overhung housing for enclosing a contact member, a fuse holder pivoted to the support and having an open side and an open top portion adapted to be closed by the support and the overhung housing respectively when the holder is in closed posi-

tion, overlapping means on the housing and the holder for preventing rotary movement of the holder when the holder is in closed position and means for permitting relative movement of the housing and holder for disengaging the overlapping means to permit of rotary opening movement of the holder.

13. Fuse mechanism comprising a support having an overhung housing for enclosing a contact member, a fuse holder pivoted to the support and having an open side and an open-top portion adapted to be closed by the support and by the overhung housing, respectively, when the holder is in closed position, a fusible element within the holder and accessible when the holder is in angular open position with respect to the support and connected to the contact member when the holder is in closed position, overlapping means on the housing for preventing rotary movement of the holder when the holder is in closed position and means for permitting relative movement of the housing and the holder for disengaging the overlapping means to permit of rotary opening movement of the holder.

In testimony whereof, we have hereunto subscribed our names this 28th day of February, 1921.

BASCUM O. AUSTIN.
WILLIAM G. HORN.
